UNITED STATES PATENT OFFICE.

JOHN C. COX AND LOWRY ARNOLD, OF ATLANTA, GEORGIA.

LIFE-SAVING APPARATUS.

1,087,352.

Specification of Letters Patent. Patented Feb. 17, 1914.

Application filed June 13, 1912. Serial No. 703,530.

To all whom it may concern:

Be it known that we, JOHN C. COX and LOWRY ARNOLD, citizens of the United States, residing at Atlanta, Fulton county, 5 State of Georgia, have invented certain new and useful Improvements in Life-Saving Apparatus, of which the following is a specification.

This invention relates to life saving apparatus and more particularly to an equipment suitable for an ocean going vessel. The draw-back to the carrying of a great number of life boats to accommodate the passengers of a large liner is to a great extent due to a lack of space.

It is one of the objects of this invention to provide additional equipment for a vessel of dependable life saving appliances, such as rafts and the like which may be 10 readily stored in a small space when not needed and which will be immediately available in cases of emergency.

Another object is to provide a mechanism controllable from any of several convenient 15 positions by means of which the life saving devices may be promptly brought into condition for service.

Another object is to provide a simple and compact life raft construction adapted to 20 use under such conditions as above described.

With the foregoing and other objects in view the novel features of the invention will 25 be apparent from the following description taken in connection with the drawings, in which:

Figure 1 is a cross section of a ship showing the improved life saving apparatus applied thereto, for the purpose of more 30 clearly illustrating the invention, a compartment containing life saving appliances is shown closed and another is shown open and the rafts in the latter are being discharged therefrom. Fig. 2 is an enlarged 35 detail view of a closed compartment and mechanism for discharging the rafts therefrom. Fig. 3 is a plan view of the air-operated raft discharging mechanism, parts thereof being broken away. Fig. 4 is a detail 40 view of the releasable connection between a raft and the plunger for moving the same. Fig. 5 is a plan view of one of the rafts, parts thereof being broken away to show the interior construction. Fig. 6 is a side elevation of a raft. Fig. 7 is a cross 45 section along the line 7—7 of Fig. 5 showing

more in detail the connection of the individual cells of the raft to the central supply duct running longitudinally of the raft. Fig. 8 is an enlarged detail view of a modified form of compartment. Fig. 9 is a perspective view of a part of the side of a ship having such a compartment as shown in Fig. 8, the door of the compartment being swung open and some of the rafts discharged. Fig. 10 shows a side view of a vessel having compartments therein, the trap doors closing the compartments being open and the rafts discharged therefrom simultaneously. Fig. 11 is a vertical cross section of one of the compartments showing the position of the raft on the inclined floor 50 therein. Fig. 12 is a view along line 12—12 of Fig. 11 looking in the direction of the arrow, showing the arrangement of the hose and raft in the compartment.

Referring to the drawings 10 designates the hull of a ship of any ordinary or preferred form and is sub-divided by a number of horizontal decks as is usual. The boiler, 55 engine and dynamo room is located on the lower deck 11, and on the same deck there is also air-supplying means 12 which may be an air compressor, a fan or the like. The compressor 12 is connected by pipes 13, 13 to air tanks 14, 14 located on the deck 11, or at any suitable place on the vessel. The air in the tanks 14, 14 is maintained at a predetermined pressure and automatic means are provided to connect the compressor to 60 the said tank to supply air thereto when the pressure falls below a certain point. Branch air supply pipes 15, 15 are connected to one or more common mains 16 having a valve 17 therein. The valve 17 is operated by a 65 hand wheel 18 connected to a stem 19 and gears 20 and 21. The hand wheel 18 may be placed at a position on the main deck, such as for instance on the bridge convenient to an officer in charge. The valve may 70 also be operated from any other suitable position or positions, such as for instance by means of a hand wheel 22 connected to the stem 19 on the deck 23.

The hold 10 has a plurality of water-tight compartments 24 and 25 located above the water line in the sides thereof. The compartments 24 and 25 as shown in Fig. 1 are of course only two of a number arranged along the sides of the ship. The compartments open outwardly overboard and are closed by the water-tight trap doors 26 and

27 which are hinged at 28 and 29 to the ship at the bottom edge of the respective compartments.

Each compartment is arranged to accommodate a plurality of life saving devices, such as the rafts R, which are normally deflated so that a large number may be stored in each compartment. Each raft is connected to the air supply and is provided with means for dropping the same overboard which will be hereinafter described. The compartments may be constructed in convenient parts of the boat so that the rafts may easily be gotten overboard and on account of the small space that is necessary it is possible for a ship to carry enough rafts of this description to accommodate several thousand passengers without taking up any excess space on the ship. On account of differences in design ship builders will probably prefer to store the rafts in different places.

Each raft is preferably built on the general lines of a mattress, but is considerably larger and two or three feet thick when inflated. Referring to Fig. 5 the outer covering or casing 30 of the raft is made of heavy duck, oil-cloth, rubberized duck, or other suitable material. The interior of the casing is divided by heavy longitudinal partitions 31 and heavy transverse partitions 32 into a number of independent chambers 33. The chambers 33 are adapted to receive the inner cells or tubes 34 which are of heavy rubber, rubberized duck or other suitable air-tight material. Each cell is connected independently to a main duct 35 running centrally through the casing 30. Each cell 34 is reinforced at its ends by thickening the material as at 36. An internally and externally threaded nipple 37 is set in the central opening 38 in the reinforced section 36. The nipple 37 has a flange 39 at one end and is held in position in the opening 38 by means of a washer 40 and a lock nut 41, thereby maintaining an air-tight connection of the nipple to the cell. A plurality of valve connections are provided on the opposite sides of the main duct 35 in the casing to receive the nipples 37 on the cells 34. An externally threaded nipple 42 having a flange 43 is set in an opening 44 in the side of the wall of the duct 35 and is held in place by means of a washer 45 and a lock nut 46. Inside the nipple 42 and integral therewith near the outer end thereof there is a spider 47 which at its center forms a bearing for the stem 48 of a check valve 49 which seats on a curved portion 50 at the outer end of the nipple 42. The spider 47 also forms a seat for a spring 51 which bears against an adjustable nut 52 on the outer end of the valve stem 48. When it is desired to connect the cell 34 to the main duct 35 the nipple 37 engages over the outer

end of the nipple 42 and a soft rubber gasket 53 is confined between the nut 46 and the inner end of the nipple 37 to form an air-tight connection. The adjustable nut 52 will allow the adjustment of the valve spring 51 and the pressure at which the valve opens may be varied.

One end of the central duct 35 extends through the outer wall of the casing 30 and has a knob or ball 54 on the end thereof which forms a part of a ball-and-socket joint to be described. The outer casing has straps 55 riveted or sewed to the top and bottom thereof so that in case either side of the raft falls there will be means to catch hold of the same. The sides of the raft have ropes 56 attached thereto and other ropes 57 so that anyone in the water may be able to draw himself up to the raft or hang onto the same should the raft capsize. As shown in Fig. 6 the side walls of the raft have slits 58 therein which correspond to the center of the chamber 33 and are provided with lacing 59. The inner tube or cell 34 may be removed through a slit 58 when the cell has been punctured or is out of commission, and when another has been put in its place and screwed onto the nipple 42 connected to the duct 35 passing centrally through the raft, the slit may be laced up. Centrally in the outer end of the tube 34 there is a release valve 60 which projects through the slit 58 and is for the purpose of releasing the air in any individual compartment when it is desired to renew the inner tube or deflate the raft. It will be noticed that the raft being made in sections each chamber and cell is independent of the others and in case of injury or the puncture of any cell the raft will still remain afloat, due to the buoyancy of the remaining cells.

In order to open the trap doors, inflate the rafts in the chambers and cast them overboard the following mechanism is provided: Two or more branch pipes 61 and 62, depending on the number of compartments, are connected to the main air supply pipe 16 and each terminates in a cross pipe 63, from each of which there is a connection 64 to a plurality of cylinders 65, 651, 652, 653, 654, 655, 656, 657 and 658. The cylinders all enter the compartment and correspond to the number of rafts there are in the compartment. From the branch pipe 62, as shown in Fig. 2, there is also a connection 66 to the end of the cylinder 65. A hollow plunger 67 operates in the cylinder 65 and corresponding hollow plungers 671, 672, 673, 674, 675, 676, 677 and 678 operate in the corresponding cylinders 651 to 658. Each of the said plungers 67 to 678 has a slot 68 in its lower surface which at times registers with the opening into the connections 64.

Depending from the outer end of each plunger there is a raft R which is connected thereto by means of a ball-and-socket joint S. The ball-and-socket joint comprises the socket nipple member 69 which is screwed into the end of each plunger 67 to 678. The outer end of the socket member 69 is of resilient material and is slotted to provide resilient tangs 70 to accommodate the ball 54 on the end of each duct 35. To provide an air-tight connection between the ball and socket a packing ring 71 is set in the ball 54. The ball 54 also has the check valve 72 which is seated against the seat 73 when the raft is released. A valve 74 when closed seats against the seat 74' in the socket member 69. The valve 74 has a stem 75 which extends downwardly and is guided by a spider 76 on the socket member 69. The lower end of the valve stem 75 has a plate 77 connected thereto which normally rests on the end of the ball 54 and holds the valve 74 from its seat. When the raft is inflated and the ball and socket members 25 pushed apart the valve 74 will drop to its seat and close the opening 78 which it controls.

In operation air having been admitted to branch pipe 62 the connection 66 which is 30 permanently connected to cylinder 65 and branch pipe 62, will admit air to cylinder 65 and force the hollow plunger 67 outwardly. As soon as the slot 68 in the hollow plunger 67 starts to pass over the connection 64 air will be conducted to the interior of the plunger 67 and inflate the raft connected thereto at the outer end. A spring-pressed stop pin 79, of which there are a plurality, engages through the cylinder wall into a recess 80 in the surface of the plunger to prevent the latter from being pushed out of the cylinder.

Connected with the cylinder 65 intermediate the ends thereof there is a pipe 81 which establishes communication between the cylinder 65 and the head end of cylinder 651 and similar pipes 811 to 817 establish communication in a similar manner between cylinders 651 to 658.

It will be noticed that there will be no transfer of air from cylinder 65 to cylinder 651 until the plunger 67 has reached the end of its stroke and the stop pin 79 engages in the recess 80. While the plunger 55 67 is moving outwardly the raft at the end of the same is inflated and then released. When the end of the plunger reaches the limit of its stroke the end of pipe 81 connected to cylinder 65 will be exposed and 60 air will be conducted to cylinder 651 from branch pipe 62 through the connection 66, cylinder 65 and pipe 81.

The plunger 671 is of the same length as the plunger 67, but the end thereof is disposed slightly back of the end of plunger

67 to allow for the thickness of a raft. The plunger 671 is hollow and has a raft depending from its end which is releasable therefrom and the plunger discharges the said raft all in the same manner as described for 70 plunger 67. This applies also to plungers 672 to 678 each succeeding plunger operating when the preceding one reaches the end of its stroke and being set slightly back of the preceding one to accommodate the necessary 75 number of rafts, thus one by one the plungers discharge the rafts from the compartment 25 and drop them overboard as is indicated in Fig. 1.

The operating mechanism for the doors 80 is actuated at the same time that air is turned on at the valve 17. The latch 82 of the door is the end of the rod of piston 83 operating in air cylinder 84. The pipe 85 connected permanently to pipe 16 is connected at a point below the piston head 83 so that air entering the cylinder will immediately force the piston up and release the door 27. The springs in the hinges 29 will immediately throw the door outwardly. 90 However, if said springs fail to act promptly the plunger 67 will force the door open.

Figs. 8 and 9 show a modified form which in some instances may be preferable as it 95 may be desirable to dispense with mechanism which might fail to operate at the critical time on account of the fact that it remains idle so long and may become stuck.

The branch pipe 62' shown in Fig. 8 is 100 in most respects similar to branch pipes 61 and 62 and is connected to the main 16. The branch pipe 62' terminates in the water-tight compartment 25' which in most respects is similar to compartments 24 and 105 25. The compartment 25' is closed by a water-tight door 86 hinged at 87. The door 86 is held closed by a latch 88 which is released by air supplied to the pipe 89 and cylinder 90 from the branch pipe 62'. 110

The bottom 91 of the compartment 25' is inclined downwardly to the door so that the rafts when deflated or inflated will slide out by gravity and be automatically discharged therefrom without requiring the 115 use of plungers or other pushing devices.

The end of the branch pipe 62' which terminates in the compartment 25' has a cross pipe 92 connected thereto which extends the length of the compartment and has a number 120 of outlets 93. Each of the outlets 93 has connected thereto a flexible air hose 94, the end of which is connected to a raft and provided with a socket to receive the ball 54 on the end of the duct 35 of a raft as shown in 125 Fig. 4. When the rafts are deflated the hose may be coiled to lie against the raft so they will not take up very much space, as is shown. When the air is admitted to pipe 62' the door latch will be released and the 130

springs and hinges 87 will throw the door out. If the door sticks the inflating rafts will force it out by expanding against the same. The rafts whether fully inflated or not will be forced out and by gravity will simultaneously slide overboard where if not already inflated they will be completely inflated through the hose connection 94 and then will be automatically released. If a 10 raft should fail to be released from a hose or if it should be impossible to break the connection at the coupling, the hose may be readily cut loose from the raft.

The operation of the form of invention 15 shown in Figs. 1 to 7 will be briefly stated. Air being admitted to the pipe 16 by the opening of valve 17 at the wheel 18 or elsewhere about the ship will admit air to both branches 61 and 62 and such other 20 branches as are connected to the air supply. The operation of the discharging mechanism connected to branch 61 is the same as that connected to branch 62 and the latter only will be described. Air from 25 branch 62 will be admitted to cylinder 65 through the connection 66 and the plunger 67 will be forced outwardly carrying therewith the raft depending from the end thereof. In the meantime air has also been admitted to the pipe 85 and the door latch 82 30 has been operated and the door has been opened. When the slot 68 in the hollow plunger 67 passes over the connection 64 air is admitted to inflate the raft at the end of 35 the plunger and as soon as a predetermined pressure in the same is reached the members 70 of the socket spread and release the ball therefrom dropping the raft overboard. As soon as the plunger reaches the limit of its 40 stroke which is determined by the stop pin 79 engaging in the recess 80, the end of the pipe 81 opening into cylinder 65 will be exposed and air will be conducted through said pipe to the next cylinder where the step will be 45 repeated and so on until the rafts are all discharged.

In Figs. 8 and 9 air admitted to branch pipe 62' is conducted to cylinder 90 through pipe 89 and operates latch 88 to open the 50 door 86. At the same time the rafts in the compartment 25' are being inflated and as soon as the door is opened they will simultaneously slide down the inclined floor 91 and be discharged from the said compartment.

In Fig. 10 a series of small doors 86' are shown in the side of a ship. Each of these doors is hinged, opens outwardly and is of slightly greater dimensions than the end dimensions of a raft R' in the compartment which the door closes.

The compartment has an inclined floor 91' slanting outward at an angle of about 45 degrees and which may be of polished material so that the raft will not stick. The in-

stant the doors 86' are opened by operating mechanism similar to that in the other views, the raft R' in each compartment will be dropped overboard by gravity. In this manner the large number of compartments in opposite sides of the vessel may discharge their contents into the sea simultaneously and within a very short time every raft on the ship can be put overboard. The compartments may accommodate one or more rafts 70 apiece, and are arranged so as not to deface the side of the ship or may be arranged between the walls of the vessel thereby not taking up any space inwardly.

The hose 93' connects each raft R' to its air supply pipe 92' which latter is connected to a common branch 62'' which is controlled from any suitable place aboard the vessel as heretofore described. The hose is laid in consecutive layers as shown in Fig. 80 12 instead of being coiled as shown in Fig. 9. There will then be no possibility of twists or kinks in the hose, which is liable to happen when the raft having the coiled 95 hose is discharged overboard. Air to operate the latch 88' working in cylinder 90' is supplied by pipe 89' connected to pipe 92'. Therefore the doors will drop immediately when the air supply is turned on and the rafts will discharge overboard simultaneously at all parts of the ship.

It will be seen that the invention provides a simple and practical means of carrying adequate life preserving appliances for several thousand passengers without taking up 100 any excess space on the ship. The rafts when deflated may readily be packed away in a very small space and may be filled without any delay and promptly brought into service. Furthermore it will be impossible 105 to sink rafts of the construction shown and there will be very little danger of capsizing. Persons may also jump from the deck of the boat onto these rafts without danger of serious injury.

It will be clear that numerous modifications may be made without departing from the spirit of the invention and it is therefore not intended that the invention be limited to the exact details as shown and described.

Having thus described the invention what is claimed is:

1. The combination with a ship provided with a compartment therein opening overboard, of a door normally closing the said compartment, life preserving means in said compartment, and fluid operated mechanism for opening said door and positively discharging the life preserving means from the 120 compartment.

2. The combination with a ship having a normally closed compartment provided with a downwardly and outwardly inclined floor, of normally deflated life preserving means 125 130

- arranged in the compartment, fluid conducting means leading into the compartment and to which the life preserving means is releasably connected, and means for opening the compartment to permit the automatic discharge of the life preserving means from the said compartment and for causing the release of said life preserving means from the fluid conducting means.
- 10 3. The combination with a ship having a compartment therein opening overboard, of inflatable life preserving means arranged in the compartment and remotely controllable means for inflating the life preserving means and discharging the same from the compartment.
- 15 4. The combination with a ship provided with a compartment therein opening overboard, of a water-tight door closing the compartment, inflatable normally deflated life rafts in the compartment, means connecting said rafts to a source of air under pressure, and means operable at will for inflating the rafts, opening the door and discharging the 25 rafts from the compartment.
- 20 5. The combination with a ship provided with a compartment therein, of inflatable life rafts in the compartment, means releasably connecting said rafts to an air supply, and means to control the air supply to inflate the rafts and discharge the same from the compartment.
- 25 6. The combination with a ship provided with a plurality of compartments therein situated above the water line, of inflatable normally deflated life rafts in the compartments, means releasably connecting the rafts to an air supply, and means for controlling the air supply to inflate the rafts and discharge the same overboard.
- 30 7. In a life raft, the combination with an outer casing, of a plurality of inner cells in said casing comprising separate air-tight chambers, a duct extending into the casing and adapted to be releasably connected to a source of air, each of said inner cells being connected to said duct, and a check valve in the connection between each of said cells and the duct.
- 35 8. In a pneumatic life raft, the combination with an outer collapsible casing, of a plurality of independent collapsible cells arranged in the casing and constituting separate air-tight chambers, a duct extending into the casing, means for releasably connecting the duct to an air supply, means for connecting each of the cells to the duct, and a check valve in the connection between the cells and the duct.
- 40 9. In a pneumatic life raft, the combination with an outer collapsible casing, of a plurality of independent chambers therein, a collapsible cell in each chamber, an air supply duct extending into the casing, and means for detachably connecting the cells to the duct.
- 45 10. In a pneumatic life raft, the combination with an outer collapsible casing, of a plurality of independent chambers formed by longitudinal and transverse partitions in the casing, the casing having openings therein to allow access to the interior of each of said chambers, a collapsible air-tight cell adapted to be introduced into each of the chambers through the openings in the casing, an air supply duct extending into the casing, and means for connecting the cells to the duct.
- 50 11. The combination with a marine vessel, of life saving devices arranged about the vessel and concealed from view, and fluid operated mechanism for mechanically and positively unloading said devices into the sea.
- 55 12. The combination with a ship, of a plurality of compartments arranged in the hold thereof, life saving devices in the compartments, fluid operated means for opening the compartments and discharging the devices into the sea.
- 60 13. The combination with a ship, of a plurality of compartments arranged in the hold thereof, an air supply pipe, a plurality of inflatable life rafts in each compartment releasably connected to said air supply pipe, and means for admitting air to the pipe to inflate the rafts and discharge the same from the compartments.
- 65 14. The combination with a ship, of a compartment arranged therein, an air supply pipe entering said compartment, an inflatable raft connected to the pipe, means for admitting air to the pipe, and means for automatically releasing the raft from the pipe when the raft has been inflated.
- 70 15. The combination with a ship, of a compartment arranged in the side thereof, an air supply pipe entering the compartment, an inflatable raft flexibly connected to the pipe, means for admitting air to the pipe and raft, and means for automatically releasing the raft from its flexible connection to the pipe when the raft has been inflated.
- 75 16. The combination with a ship, of compartments arranged in the hull thereof, air supply pipes entering the compartments, rafts connected to the air supply pipes, means for admitting air to the pipes and rafts, and means for discharging the rafts from the compartments and automatically releasing the rafts from the air supply pipes.
- 80 17. The combination with a ship, of compartments arranged in the hull thereof, doors normally closing the compartments, air supply pipes entering the compartments, pneumatic deflated rafts disposed in the compartments and connected to the pipes, means for admitting air to the pipes to

simultaneously release the doors and discharge the rafts from the compartments.

18. The combination with a ship, of compartments arranged therein, air supply pipes entering the compartments, pneumatic deflated rafts in the compartments, means releasably connecting said rafts to the pipes comprising a socket and ball coöperating therewith, means for admitting air to the pipes to inflate the rafts and discharge them from the compartment.

19. The combination with a ship, of compartments arranged therein, air supply pipes entering the compartments, pneumatic deflated rafts in the compartments, means releasably connecting said rafts to the pipes comprising a socket and ball coöperating therewith, a valve in said ball and socket connection adapted to be closed on release of the raft, and means for admitting air to the pipes to simultaneously inflate the rafts and discharge them from the compartment.

20. The combination with a ship, of compartments therein, air supply pipes entering the compartments, normally deflated pneumatic life preserving devices in the compartments, means releasably connecting said devices to the pipes, means for admitting air to the pipes to inflate the normally deflated

devices, and valves in said connecting means adapted to close the pipe and the inflated devices to prevent the escape of air therefrom.

21. The combination with a ship, of watertight compartments therein, doors closing the compartments, normally deflated pneumatic rafts in the compartments, means releasably connecting said rafts to the pipes, means for admitting air to the pipes to inflate the rafts, open the doors and discharge them successively overboard, and means in said connecting means adapted to prevent the escape of air from said pipes and rafts when the latter are released from the pipe.

22. In a pneumatic raft, the combination with an outer casing, of a plurality of cells in said casing constituting separate airtight chambers, and a duct extending into said casing and communicating with each cell, said duct being adapted to be connected to a source of air under pressure and automatically releasable therefrom.

In testimony whereof we affix our signatures in presence of two witnesses.
